UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 21, 1924. Serial No. 733,394.

My invention relates to railway traffic controlling apparatus and particularly to apparatus of the type comprising train carried governing means controlled by energy received from the trackway. More particularly, my invention relates to the trackway portion of such apparatus.

I will describe several forms and arrangements of apparatus embodying my invention, and will then point out the novel features thereof in claims.

In the accompanying drawings, Fig. 1 is a diagrammatic view showing one form of trackway apparatus embodying my invention. Figs. 2 and 3 are views showing modifications of the apparatus illustrated in Fig. 1, and also embodying my invention. Fig. 4 is a fragmental view showing one modification of a portion of the apparatus shown in Fig. 2 and also embodying my invention.

Similar reference characters refer to similar parts in each of the four views.

Referring first to Fig. 1, the reference characters 1 and 1^a designate the track rails of a railroad over which traffic normally moves in the direction indicated by the arrow. These track rails are divided, by means of insulated joints 2, into a plurality of successive track sections A—B, B—C, C—D, etc.

Each track section is provided with a track relay designated by the reference character R with a suitable exponent and connected across the rails adjacent the entrance end of the section. Track circuit current for controlling such track relays is supplied to each track section from some suitable source of direct current, such as a battery 8, connected across the rails adjacent the exit end of the section. A resistor 6 is interposed between each track battery 8 and one rail of the associated section in the usual and well known manner.

Each section is further provided with a trackway signal designated by the reference character S with an exponent corresponding to the location. These signals may be of any suitable form and are here shown as 3-indication semaphore signals.

Each signal S is controlled by the associated track relay in the following manner. Referring, for example, to signal S^c, when

relay R^c is energized, a circuit is closed over which current flows from a suitable source of energy, such as battery J^c, through wire 15, front contact 27 of relay R^c, wire 28, operating mechanism of signal S^c, wire 29, front contact 11 of relay R^c, and wire 32 back to battery J^c, and signal S^c then displays a caution indication. If relay K^c is also energized, as will be described herein-after, current flows from battery J^c, through wire 15, front contact 27 of relay R^c, wire 30, front contact 10 of relay K^c, wire 31, operating mechanism of signal S^c, wire 29, front contact 11 of relay R^c, and wire 32 back to battery J^c. When this circuit is closed signal S^c indicates proceed. When relay R^c is de-energized both operating circuits for signal S^c are opened and the closing of back contact 27 of relay R^c short circuits the operating mechanism of signal S^c and the signal then displays a stop indication.

Each signal controls a pole changer 9 interposed in circuit with the track battery 8 for the section next in rear. Each pole changer 9 is arranged to occupy one position when the associated signal indicates proceed or caution, and a different position when such signal indicates stop. When a signal, such as signal S^c, indicates proceed or caution, section B—C is supplied with track circuit current of one polarity, which I shall call "normal" polarity, and relay R^b is energized in the normal direction, swinging armatures 19 and 24 to the left. When signal S^c indicates stop, section B—C is supplied with track circuit current of the opposite polarity, which I shall term "reverse" polarity, and relay R^b is energized in the reverse direction to swing armatures 19 and 24 to the right.

Associated with each track relay is a line relay designated by the reference character K with an appropriate exponent. Referring particularly to line relay K^b, this relay is provided with a circuit which may be traced from battery J^c through wires 15 and 16, front contact 17 of track relay R^c, wire 18, normal contact 19 of relay R^c, wire 20, winding of relay K^b, wire 21, circuit controller 14 operated by signal S^b, wires 22, 23 and 25, circuit controller 13 operated

by signal S^c , and wire 26 back to battery J^c . This circuit is closed only when relay R^c is energized in the normal direction and both signals S^p and S^c are indicating proceed or caution.

Means are also provided for supplying each section with alternating train controlling current. For this purpose each section is provided with a track transformer designated by the reference character T with an appropriate exponent and having its secondary winding 4 connected in series with the corresponding track battery 8 and pole changer 9. An impedance 7 is interposed between the secondary 4 of each track transformer T and the associated pole changer 9. Each transformer T is at times supplied with alternating current from an associated line transformer designated by the reference character H with an exponent corresponding to the location. The primary 34 of each line transformer H is constantly supplied with alternating current from some suitable source, such as an alternator M , over line wires 3 and 3^a. Referring, for example, to track transformer T^c , current flows at times from secondary 33 of line transformer H^c through wire 35, normal contact 24 of relay R^c , wire 36, front contact 37 of relay R^c , wire 38, circuit controller 12 operated by signal S^c , wire 39, primary 5 of transformer T^c , and wire 40, back to transformer H^c . This circuit is closed only when relay R^c is energized in the normal direction and signal S^c indicates caution or proceed. Each of the remaining track transformers is controlled in the same manner as just described for transformer T^c , and it is therefore plain that each section is supplied with train controlling current when the track relay for the section next in advance is energized in the normal direction.

It should be here pointed out that the trackway apparatus herein shown and described is suitable for co-operation with train carried governing means so that when the train occupies a stretch of track supplied with alternating train controlling current a less restrictive indication, as a proceed indication, is received on board the train, whereas when such supply is interrupted the train receives a more restrictive indication, such as a stop indication.

As shown in the drawing the section to the right of point D is occupied by a train, indicated diagrammatically at V . Relay R^p is therefore de-energized. As a result signal S^p indicates stop, and relay K^p is de-energized. The circuit for transformer T^p is open at contact 12 and at relay R^p , so that no train controlling current is being supplied to section C—D. Pole changer 9 operated by signal S^p is reversed and section C—D is therefore supplied with direct track circuit current of reverse polarity.

Relay R^c is therefore energized in the reverse direction. The circuit for relay K^c is now open at circuit controller 13 of signal S^p and at relay R^p , so this relay is de-energized. Signal S^c therefore indicates caution. The circuit for transformer T^c is, however, open at normal contact 24 of relay R^c , so that section B—C is not supplied with train controlling current. Track circuit current of normal relative polarity is supplied to section B—C and relay R^p is energized in the normal direction. Relay K^p is de-energized, however, its circuit being open at normal contact 19 of relay R^c . Signal S^p therefore indicates caution. Section A—B is supplied with track circuit current of normal polarity and also with train controlling current. Relay R^a is energized in the normal direction, relay K^a is energized, and signal S^a indicates proceed. Under these conditions the section to the left of A is supplied with track circuit current of normal polarity and also with train controlling current.

It will be observed that the signals are controlled in accordance with what is known as "three block signaling", that is, the two signals in the rear of a stop signal indicate caution, and the third signal in the rear of a stop signal indicates proceed.

If, with the apparatus as shown in the drawing, a second train proceeds through the stretch of track, it will receive a proceed indication as far as point B where the interruption of train controlling current will cause the train to receive a stop indication. This stop indication persists throughout sections B—C and C—D, and if the train enters the section to the right of point D, it will continue to receive a stop indication, the train controlling current being shunted away from the second train by the wheels and axles of the train V already occupying the section.

Referring now to Fig. 2, the apparatus here shown is similar to that shown in Fig. 1 with the exception that the functions of circuit controllers 12, 13 and 14 are performed by other contacts. In Fig. 2 each section is provided, as in Fig. 1, with a track way signal S , a track relay R , and line relay K . Each track relay R is responsive, as before, to reversals of the polarity of the direct current flowing in the track rails, and controls the associated trackway signal S . Referring particularly to signal S^c , when the associated track relay R^c is energized, current flows from battery J^c through wire 15, front contact 27 of relay R^c , wire 28, operating mechanism of signal S^c , wire 29, front contact 11 of relay R^c , and wire 32 back to battery J^c . This circuit is closed when relay R^c is energized in either direction and signal S^c will then indicate caution. When relay R^c

R^c is energized in the normal direction current flows from battery J^c , through wire 15, front contact 27 of relay R^c , wire 30, normal point of contact 19 of relay R^c , wire 31, operating mechanism of signal S^c , wire 29, front contact 11 of relay R^c and wire 32 back to battery J^c and signal S^c indicates proceed. 5

5 wire 31, operating mechanism of signal S^c , wire 29, front contact 11 of relay R^c and wire 32 back to battery J^c and signal S^c indicates proceed.

Each line relay K is controlled by the associated track relay and by the track relay for the section next in advance. For example, the circuit for relay K^c may be traced from battery J^p , through wires 15 and 16, front contact 17 of relay R^p , wire 41, front 10 contact 42 of relay R^c , wire 36, winding of relay K^c and wires 42 and 23 back to battery J^p . This circuit is closed only when relays R^c and R^p are energized, under which conditions relay K^c is energized.

10 When relay K^c is energized secondary 4 of train control transformer T^c is connected in series with impedance 7, track battery 8 and resistor 6, with rails 1 and 1^a of section B—C, over front contacts 43 and 44 of relay K^c . Under these conditions section B—C is supplied with direct track circuit current of normal relative polarity and also with alternating train controlling current. When, however, relay K^c is de-energized secondary 15 4 of transformer T^c is disconnected from the rails of section B—C and track battery 8 is connected directly with the rails of section B—C through resistor 6. It should be noted however that under these conditions the polarity of the direct track circuit current supplied to section B—C is reversed. The primary 5 of each track transformer T is constantly supplied with alternating current, as before, from an associated line transformer H and each line transformer is constantly supplied with alternating current over line wires 3 and 3^a from an alternator M .

As shown in the drawing the section to the right of point D is occupied by a train indicated diagrammatically at V. Track relay R^p is therefore de-energized and signal S^p therefore indicates stop. Line relay K^p is de-energized and section C—D is supplied with track circuit current of reverse polarity but not with alternating train controlling current. Relay R^c is therefore energized in the reverse direction and signal S^c then indicates caution. Relay K^c is deenergized, its circuit being open at front contact 17 of relay R^p . Section B—C is therefore supplied with direct current of reverse polarity but not with train controlling current. Under these conditions relay R^p is energized in the reverse direction and signal S^p also indicates caution. The circuit for relay K^p is now completed over front contacts of relays R^c and R^p and relay K^p is therefore energized. As a result direct current of normal polarity is supplied to section A—B and this section is also supplied with alternating 20 train controlling current from transformer T^p . Relay R^A is then energized in the normal direction, relay K^A is energized, and signal S^A indicates proceed. If now a second train moving from left to right enters the stretch of track shown in the drawing it will receive a proceed indication as far as point B, where the interruption of train controlling current will cause a stop indication to be received on the train as it proceeds through sections B—C and C—D. 70

In Fig. 4 I illustrate an alternative arrangement for controlling the train controlling current and the polarity of the track circuit current by the line relay K . In this view three contact armatures are used instead of two as in Fig. 2 and the primary 5 of the train controlling transformer T is carried over a front contact 45 of relay K . It will be observed that with this arrangement the secondary 4 of transformer T is constantly connected in series with battery 8 and that contacts 43 and 44 serve as a pole changer to control the connection of the terminals of this series combination with the track rails. When relay K is de-energized the circuit for transformer T is opened at contact 45 and the secondary winding 4 then functions simply as an impedance in series with battery 8. 85

Under some conditions of operation the lengths of the track sections may be so great that it is desirable to divide each of the sections into two subsections. When this is true the arrangement illustrated in Fig. 3 may be used. In this modification each of the sections A—B, B—C and C—D, etc. is divided into a forward and rear subsection by means of insulated joints 2, located at an intermediate point X in the section. In addition to the track relay R connected across the rails adjacent the entrance end of each section, a second track relay, designated by the reference character r with an exponent corresponding to the location is connected across the rails adjacent the exit end of each section. A battery 8 and a resistor 6 are connected in series across the rails to the right of point X in each section and a track transformer T^x has its secondary 4 connected in series with an impedance 7 and resistor 6 and a track battery 8 across the rails to the left of point X in each section. A second train control transformer designated by the reference character T with an exponent corresponding to the location has its secondary winding 4 connected across the rails adjacent the exit end of each section. Each track relay R in Fig. 3 is of the two-position type but each section is provided with a polarized relay designated by the reference character G with an appropriate distinguishing exponent. Each section is provided with a line relay K as in the preceding views. 90

Each section is further provided as in 100

Figs. 1 and 2 with a trackway signal S having associated therewith three circuit controllers 12, 13 and 14 and each trackway signal S also controls a pole changer designated by the reference character 9^a. Referring particularly to section C—D, the circuit for polarized relay G^c may be traced from battery J^p , through wires 46 and 47, pole changer 9^a operated by signal S^p , wire 57, front contact 56 of track r^p , wire 55, front contact 54 of relay R^c , wire 53, winding of relay G^c , wire 52, front contact 51 of relay R^c , wire 50, front contact 49 of relay r^p , wire 48, pole changer 9^a and wires 58 and 58^a back to battery J^p . It is therefore plain that when relays R^c and r^p are energized, relay G^c is supplied with current of one polarity when signal S^p indicates caution or proceed and with current of the other polarity when signal S^p indicates stop. The remaining polarized relays G are controlled in a manner similar to that just described for relay G^c .

When relay G^p is energized current flows from battery J^p , through wire 46, front contact 78 of relay G^p , wires 79 and 80, operating mechanism of signal S^p , wire 81, front contact 82 of relay G^p and wire 83 back to battery J^p and signal S^p then indicates caution. Another circuit for signal S^p may be traced from battery J^p , through wire 46, front contact 78 of relay G^p , wires 79 and 80, front contact 84 of relay K^p , wire 85, operating mechanism of signal S^p , wire 81, front contact 82 of relay G^p , and wire 83 back to battery J^p . This circuit is closed only when relays G^p and K^p are both energized, under which conditions signal S^p indicates proceed. The circuits for the remaining signals are similar to those just traced for signal S^p .

When signals S^c and S^p both indicate caution or proceed and relay G^p is energized in the normal direction and current flows from battery J^p , through wire 46, front contact 59 of relay G^p , wire 60, normal point of contact 61 of relay G^p , wire 62, winding of relay K^c , wire 63, circuit controller 14 operated by signal S^c , wire 64, circuit controller 13 operated by signal S^p and wires 65 and 58^a back to battery J^p , and relay K^c is then energized.

Train controlling current is at times supplied to the train control transformers for each section from a line transformer H supplied with alternating current from an alternator M as in Figs. 1 and 2. A circuit may be traced from secondary 33 of transformer H^p , through wire 66, normal point of contact 67 of relay G^p , wire 68, front contact 69 of relay G^p , wire 70, circuit controller 12 operated by signal S^p , wire 71, front contact 72 of relay R^p , wire 73, primary 5 of transformer T^p and wire 40 back to secondary 33 of transformer H^p . The circuit

just traced is provided with a branch which passes from wire 73, through wire 74, front contact 75 of relay r^p , wire 86, primary 5 of transformer T^x , wire 87 and back to wire 40. It follows that when signal S^p indicates proceed or caution and relay G^p is energized in the normal direction train controlling current is supplied to subsection X—D; and when relay r^p is energized, signal S^p indicates proceed or caution and relay G^p is energized in the normal direction, train controlling current is supplied to subsection C—X by transformer T^x .

As shown in the drawing, the section to the right of point D is occupied by a train V and relay R^p is therefore de-energized. The circuit for relay G^p is, therefore, open and the closing of back contact 88 on relay R^p short circuits this relay to prevent it from picking up improperly. Relay G^p being de-energized, signal S^p indicates stop, thereby opening circuit controllers 12, 13 and 14 and reversing pole changer 9^a. Relay K^p is therefore de-energized and furthermore the circuits for transformer T^p and transformer T^x in section C—D are interrupted. Subsection X—D is supplied with direct current by battery 8 but not with train control current, and relay r^p is therefore energized. Similarly, subsection C—X is supplied with direct current but not with train control current and relay R^c is also energized. Under these conditions the circuit for relay G^c is complete, but pole changer 9^a operated by signal S^p is now reversed and therefore relay G^c is energized in the reverse direction. Signal S^c therefore indicates caution and relay K^c is de-energized, the circuit for this relay being open at front contact 59 of relay G^p . Subsections B—X and X—C are each supplied

with direct track circuit current from a track battery 8 located adjacent point X but the circuit for both train control transformers associated with these subsections are open at normal point of contact 67 of relay G^c and therefore neither subsection is provided with train controlling current. Relays R^p and r^c are both energized and relay G^p is energized in the normal direction. The circuit for relay K^p is open, however, at normal point of contact 61 of relay G^c and this relay is therefore de-energized. Signal S^p then indicates caution. The closing of normal point of contact 67 of relay G^p completes the circuit for transformer T^p and transformer T^x associated with section A—B and train controlling current is therefore supplied to subsection A—X and subsection X—B from train controlling transformers, one located adjacent the exit end of each subsection. Relays R^A and R^B are both energized by direct track circuit current and relay G^A is energized in the normal direction. The circuit for line relay K^A is complete over nor-

mal contact 61 of relay G^B and signal S^A therefore indicates proceed.

If, now, a second train, moving in the direction of the arrow, enters the stretch of track shown in the drawing, this train will receive a proceed indication as it moves through subsections A—X and X—B. At point B, however, the interruption of train controlling current will cause a stop indication to be received on the train and this indication will persist as the train moves successively through subsections X—C, C—X and X—D.

It will be observed that the apparatus illustrated in Fig. 3 is similar to that shown in Fig. 1 with the exception that in Fig. 3 the direct current track circuits are neutral, and polarized contacts on line relay G are used instead of polarized contacts on a track relay. Other changes in the circuits are those that are made necessary by the cut sections.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track, means for supplying said stretch with track circuit current, a polarized relay responsive to traffic conditions in advance of said stretch, and means for supplying train controlling current to said stretch when said relay is energized in one direction but for discontinuing such supply when the relay is energized in the other direction or is de-energized.

2. In combination, a plurality of successive sections of railway track, a signal for each section; means for controlling said signals so that when one section is occupied the corresponding signal indicates stop, the first signal in rear and the second signal in rear each indicate caution, and the third signal in rear indicates proceed; and means effective when one section is occupied for supplying train controlling current to the third section in rear of the occupied section but not to the first and second sections in rear thereof.

3. In combination, a forward and a rear section of railway track, a polarized relay for said forward section, means controlled by traffic conditions in advance of said forward section for supplying current of one polarity or the other to said polarized relay, a signal for said rear section, a line relay for controlling said signal, and means effective when said polarized relay is energized in one direction but not when such relay is energized in the other direction for energizing

said line relay and supplying train controlling current to the rails in rear of said rear section.

4. In combination, a plurality of successive sections of railway track, a polarized track relay for each section connected across the track rails of the corresponding section, means for supplying each section with track circuit current of one relative polarity or the other depending upon traffic conditions in advance, and means for each section for supplying such section with train controlling current when the relay for the section next in advance is energized in one direction but not if such relay is energized in the other direction or de-energized.

5. In combination, a plurality of successive sections of railway track, a polarized track relay for each section connected across the track rails of the corresponding section means for supplying each section with track circuit current of one polarity or the other depending upon traffic conditions in advance, means for each section for supplying such section with train controlling current when the relay for the section next in advance is energized in one direction but not if such relay is energized in the other direction or de-energized, a line relay for each section arranged to be energized only when the track relay for the section next in advance is energized in said one direction, and a trackway signal for each section controlled by the associated line relay.

6. In combination, a plurality of successive sections of railway track, a polarized track relay for each section, means associated with each track relay for supplying the section next in rear with track circuit current of one polarity or the other according as such track relay is energized or de-energized, means also associated with each track relay for supplying train controlling current to the section next in rear when the relay is energized in one direction but not when the relay is energized in the other direction or de-energized, a line relay for each section arranged to be energized when the track relay for the section next in advance is energized in said one direction but not when such relay is energized in the other direction or de-energized, and a trackway signal for each section controlled by the track relay and the line relay associated therewith.

7. In combination, a plurality of successive track sections, a track relay for each section, means for supplying each section with track circuit current of one polarity or the other according as the section next in advance is occupied or unoccupied, and means for supplying each section with train controlling current when and only when at least the two sections next in advance of such section are unoccupied.

8. In combination, a plurality of succes-

sive track sections, a polarized track relay for each section, means for supplying each track section with track circuit current of one polarity or the other depending upon traffic conditions in advance, and means for each section effective when and only when at least such section and the section next in advance are both unoccupied to supply train controlling current to the section next in rear.

9. In combination, a plurality of successive track sections, a polarized track relay

for each section, means for supplying each track section with track circuit current of one polarity or the other depending upon traffic conditions in advance, and means for each section controlled by the track relay for such section and effective when and only when at least such section and the section next in advance are both unoccupied to supply train controlling current to the section next in rear. 15 20

In testimony whereof I affix my signature.

HERBERT A. WALLACE.
